UNITED STATES PATENT OFFICE.

ELBERT C. BANNER AND MERRITT I. TUBBS, OF BUFFALO, NEW YORK.

DESIGN FOR AN ELECTRIC HEATING LOG.

Application filed May 11, 1926. Serial No. 17,660. Term of patent 7 years.

To all whom it may concern:

Be it known that we, ELBERT C. BANNER and MERRITT I. TUBBS, citizens of the United States, residing at Buffalo, in the county of Erie and State of New York, have invented a new, original, and ornamental Design for Electric Heating Logs, of which the following is a specification, reference being had to the accompanying drawing, forming part thereof.

Figure 1 is a perspective view looking toward the front and one end of an electric heating log, showing our new design.

Figure 2 is a similar view looking at the other end and rear thereof.

We claim:

The ornamental design for an electric heating log, as shown.

ELBERT C. BANNER.
MERRITT I. TUBBS.
